CLAIM

The ornamental design for a vented urine meter, as shown and described.

DESCRIPTION

FIG. 1 is a front perspective view of our new design of a vented urine meter;

FIG. 2 is an enlarged view of the circled portion "2" in FIG. 1;

FIG. 3 is a top plan view of the vented urine meter of FIG. 1;

FIG. 4 is a front elevation view thereof;

FIG. 5 is a rear elevation view thereof;

FIG. 6 is a left side elevation view thereof;

FIG. 7 is a right side elevation view thereof; and,

FIG. 8 is a bottom plan view thereof.

The broken lines depict portions of the vented urine meter that form no part of the claimed design. The short dash-dash, long dash lines in FIGS. 1 and 2 indicate the boundary of the partial view and form no part of the claimed design. The break lines in FIGS. 1 and 3-8 represent indeterminate lengths, the break lines and portions of the article between the break lines form no part of the claimed design.
